STARCHING MACHINE

Allen R. Allsup, St. Louis, Mo., assignor to Allsup Manufacturing Company, St. Louis, Mo., a corporation of Missouri

Application March 18, 1938, Serial No. 196,721

16 Claims. (Cl. 91—31)

This invention relates generally to starching machines and more specifically to an improved starching machine adapted particularly for use in starching portions of shirts and other laundered articles, the predominant object of the invention being to provide a machine of this type which is of improved construction and arrangement, and because of such improved construction and arrangement is capable of performing its intended function in a more efficient manner than did starching machines heretofore known and used.

Starching machines such as that disclosed herein are employed in laundries which cater to the public, and in carrying on the business of such organizations speed in performing various operations required in laundering and finishing articles is of the utmost importance. Prior to this invention various starching machines have been employed in public laundries and while most of these starching machines functioned with a fair degree of success they were deficient in one respect in that it was necessary that the operator give complete attention to each article during the entire time it was being acted on by the starching machine. Obviously this situation had the effect of slowing up the starching operations for the reason that the operator of the starching machine could not turn from the starching machine to select another article and prepare it for starching until the starching machine had completed the operation of starching the preceding article. In other words, these earlier starching machines were so operated that the operator had to give his entire attention to the articles being starched throughout the entire period of time during which the articles were being starched with the aid of the machines, and could not select another article and prepare it for the starching operation until the starching of the preceding article by the machine had been completed. Thus after each starching operation of these earlier machines the machines came to rest and remained inactive while another article was being prepared for the machine.

The predominant feature of the improved machine disclosed herein is that the machine, during operation, does not require the entire attention of the operator, and therefore as soon as the operator has introduced an article into the machine and has set the machine in motion, he may turn his attention to the task of preparing another article for the machine. By the time an article passing through the machine is discharged therefrom preparation of a succeeding article for the

machine is completed and this article is immediately introduced into the machine and passes therethrough while the operator is preparing still another article for the starching operation. It is plain, therefore, that the "rest periods" of the earlier starching machines, when articles were being prepared for introduction into the machines, are entirely eliminated in the use of the machine of the present invention and therefore the time required for starching a given number of articles with the aid of the improved machine disclosed herein is substantially less than was required to starch the same number of articles with the aid of the earlier starching machines.

Fig. 1 is a vertical section of the improved starching machine.

Fig. 2 is a fragmentary side elevation of the wringer portion of the improved machine.

Fig. 3 is a fragmentary vertical section taken on line 3—3 of Fig. 4.

Fig. 4 is a vertical section taken on the staggered line 4—4 of Fig. 1.

Fig. 5 is an enlarged fragmentary section taken on line 5—5 of Fig. 1.

Fig. 6 is an enlarged fragmentary section taken on line 6—6 of Fig. 1.

Fig. 7 is an enlarged fragmentary side elevation illustrating the mercury switch which forms a part of the machine.

Fig. 8 is a plan view of the improved machine with a part thereof broken away to reveal parts of the machine which otherwise would be concealed.

Fig. 9 is a fragmentary vertical section taken through the upper portion of the machine and showing the machine in a different condition.

Fig. 10 is an enlarged section taken on line 10—10 of Fig. 4.

Referring now to the drawings, wherein is shown for the purpose of illustration, merely, one embodiment of the invention, 1 designates the frame of the machine which may be of any suitable construction and arrangement to perform its function of supporting the various parts of the machine. The frame 1 supports at its top 45 a plate 2 which is provided with a depressed portion that provides a reservoir 3 in which a body of starch solution is received. At the right-hand side of the machine as shown in Fig. 1, a channel-way 4 is formed in the top plate 2 which communicates with the reservoir 3, said channel-way being closed at its outer end by an inclined wall 4'. Disposed immediately beneath the reservoir 3 is a heating apparatus which includes an electrical heating element 5 which, in the use of the ma- 55

chine, serves to maintain the starch solution at the proper temperature.

At the right-hand end of the machine as viewed in Fig. 1, the frame of the machine includes upright elements 6 which are suitably secured together and to the main portion of the frame of the machine to provide a support for a wringer 7 which constitutes an important part of the machine. The wringer 7 includes a wringer frame 8 which includes a vertical portion 9 (Fig. 4), an overhanging top portion 10, and a depending portion 11 which extends downwardly from an end of the overhanging portion 10. The frame of the wringer 7 is completed by a portion 12 which is aligned vertically with the depending frame portion 11 but is spaced from said depending frame portion to provide an opening 13 which leads into the wringer frame. The wringer frame 8 is suitably secured in place with respect to the upright elements 6 of the frame of the machine. The overhanging portion 10, the depending portion 11, and a part of the vertical portion 9 of the wringer frame are produced by spaced apart elements which are joined together by a block portion 14 (Fig. 4) and interposed between the spaced apart elements of the overhanging portion 10, and bolted or otherwise secured thereto, are spacers 15. The overhanging portion 10 of the wringer frame supports an air cylinder 16 which is secured by means of bolts 17, or otherwise, to the spacers 15, and arranged for reciprocation within this air cylinder is a piston 18 (Fig. 1). The piston 18 has fixedly associated therewith a piston rod 19 which extends downwardly through an opening formed in the bottom wall of the cylinder, said piston rod being extended through a packing sleeve 20.

Arranged for vertical movement with respect to the wringer frame 8 is an inverted U-shaped member 21 which serves as a support for the top roller 22 of the wringer. The member 21 is guided by and moves vertically between the spaced apart elements of the wringer frame portions 9, 10, and 11, and the shaft 23 of the upper roller 22 is supported for rotation at its opposite ends in bearings formed in the opposed downwardly extended legs of the member 21. The member 21 is supported by opposed coil springs 24 which are attached at their lower ends by means of eye bolts 25 to said member 21, and at their upper ends by means of similar eye bolts 26 to the top walls of hollow elements 27 which are supported by the overhanging portion 10 of the wringer frame. As shown in Fig. 8 the hollow elements 27 are provided with base portions 27' which span the spaced apart elements of the overhanging portion 10 of the wringer frame, and said base portions are suitably secured to said spaced apart elements. The piston rod 19 is provided with a lower extension 19' of reduced diameter which extends into an opening 21' formed in the top portion of the member 21.

The wringer of the improved machine includes also a lower roller 28, the shaft 29 of which is supported for rotation in bearings 30 supported by opposed portions of the wringer frame. The lower roller 28 of the wringer is disposed immediately above the channel-way 4 previously mentioned herein and fixedly mounted on the shaft 29 of said lower roller at an end of said shaft is a sprocket wheel 31. Operating over the sprocket wheel 31 is a sprocket chain 32, said sprocket chain serving to transmit rotary motion to the sprocket wheel 31, and to the shaft 29 and lower roller 28 associated

therewith, from a sprocket wheel 33 (Fig. 4). The sprocket wheel 33 is mounted on a shaft 35 which extends through a speed reduction housing 36, wherein suitable speed reducing gearing (not shown) is contained, said speed reduction housing being supported by the frame of the machine. Rotary motion is transmitted from a shaft 37, supported by the speed reducing housing, to the shaft 35 through the speed reducing gearing within the housing 36, and rotary motion is transmitted to the shaft 37 from a motor 38 through the instrumentality of a transmission belt 39 which operates over pulleys 40 and 41 fixedly mounted respectively on the shaft 37 and the shaft 42 of the motor 38.

The improved starching machine disclosed herein includes an arm 43 which is of paramount importance. This arm is shaped as shown to the best advantage in Fig. 1, said arm being supported for pivotal movement by a pivot 44 which pivotally attaches said arm to a vertically disposed element 44' forming a part of the frame of the machine. As illustrated in Fig. 1 the arm comprises an upper portion 43a and a tail portion 43b which passes beneath the top plate 2 of the machine through an opening 45 formed through an end plate 46 of the machine. The upper portion and the tail portion of the arm 43 are shown in the drawings as being separate elements secured together by bolts 47 but obviously the entire arm may be made in one piece. At its forward end the arm 43 is provided with a head 48 of substantial width (Fig. 8) which generally is of substantially L-shaped formation in cross-section as shown in Fig. 1. Preferably this head is provided with spaced ribs 48' as shown by dotted lines in Fig. 8 which extend forwardly from the downturned rear wall of the head to the forward edge of said head. These ribs tend to prevent splashing as the head of the arm is lowered forcibly into the starch solution in the reservoir 3 as will be hereinafter explained.

The tail portion 43b of the arm 43 has mounted thereon, as shown to the best advantage in Figs. 1, 6, and 7, a mercury switch 49 which is electrically connected to a source of electrical energy and to the motor 38. Also said tail portion of said arm has attached thereto a rod 50 which is provided with a bifurcated portion 51 that embraces the tail portion of the arm, said rod being pivotally connected to the tail portion of the arm through the instrumentality of a bolt 52 which passes through aligned apertures formed through the spaced legs of the bifurcated portion and through the tail portion 55 of the arm. Slidably mounted on the rod 50 is a sleeve 53 from which trunnions 54 extend in opposite directions (see Fig. 10) and mounted on said rod 50 at points above and below the sleeve 53 are nuts 55 and 56. Interposed between the top face of the sleeve 53 and the nut 55 is a coil spring 57 and interposed between the bottom face of the sleeve 53 and the nut 56 is a coil spring 58. Because of the arrangement just described it is obvious that the sleeve 53 is supported for yielding sliding movement on the rod 50.

Secured by welding, or otherwise, to angle elements 59 forming parts of the frame of the machine is a vertical element 60 (Fig. 3) which is provided with a boss 61, and pivotally attached to said boss by means of a bolt 62 is a member 63 (Figs. 4 and 8). At one of its ends the member 63 is bifurcated as shown at 64 in Fig. 8, and the spaced legs of this bifurcated portion 64

are provided with alined apertures which receive the trunnions 54 of the sleeve 53, and at its opposite end said member 63 is bifurcated as shown at 65. The member 63 has secured thereto an arm 66 which extends parallel with said member and is projected outwardly beyond the bifurcated end 64 of said member, as shown to good advantage in Fig. 8. Pivotaly attached to the member 63 at a point inwardly of the bifurcated end portion 64 thereof is a link 67 (Fig. 4) and pivotally attached to said member 63 at the bifurcated end 65 thereof is a similar link 68. The links 67 and 68 are pivotally attached at their lower ends to valve rods 69 and 70 which extend into an air valve housing 71 which is secured to the vertical element 60 previously mentioned herein. The housing 71 contains suitable air valve mechanism of common construction which is not shown, and leading into this housing from a source of air supply is an air inlet conduit 72. From the opposite side of the housing 71 an air outlet conduit 74 leads to the top of the air cylinder 16. Preferably the air valve housing has a muffler 75 associated therewith to suppress the noise of exhausted air during operation of the machine.

Coupled to the shaft 35 by means of the coupler 76 (Fig. 4) is a shaft 77, said shaft 77 being supported for rotation by suitable bearings 78 supported by portions of the frame of the machine. The shaft 77 has fixedly mounted thereon a sprocket wheel 79 over which a sprocket chain 80 operates (Fig. 1), said sprocket chain operating also over a sprocket wheel 81 which is mounted on a shaft 82. The shaft 82 is supported for rotation by bearings 83 supported by portions of the frame of the machine. Certain links of the sprocket chain 80 have projections 84 formed thereon which serve a function to be hereinafter set forth.

In order to control movement of the arm 43 and retain it in positions to which it is moved the tail portion 43b of said arm extends between a pair of spaced plates 85 (Figs. 1 and 5). The plates are secured at their upper ends to a part of the frame of the machine and at the lower ends of said plates a headed rod 86 is associated therewith. The rod 86 is extended through alined apertures formed in the plates with the head of the rod contacting with one of the plates. Interposed between the other plate and a nut 87 is an expansible coil spring 88 which in an obvious manner forces the lower ends of the plates toward each other and thereby causes the plates to frictionally grip the tail portion of the arm 43 located between said plates whereby the tail portion of the arm will be retained in various positions to which it is moved.

In the operation of the improved starching machine disclosed herein a body of starch solution is arranged in the reservoir 3 and the operator of the machine folds a shirt, for instance, so that the collar and cuffs to be starched are arranged together. The body of the shirt is passed through the opening 13 to locate said shirt portion between the rollers of the wringer and with the collar and cuffs of the shirt extended into the starch solution in the reservoir 3. The arm 43 is then moved downwardly by the operator to the position in which said arm is shown in Fig. 9 and when so positioned the head 48 of the arm maintains the collar and cuffs of the shirt in a submerged condition in the starch solution. When the arm 43 is depressed the valve mechanism within the valve housing 71 is opened

by movement of the member 63, links 67 and 68, and rods 69 and 70, and compressed air will pass through the conduit 74 to the air cylinder 16 to move the piston 18 downwardly within said air cylinder and lower the upper roller of the wringer against the action of the coil springs 24. As the roller reaches its lowered position electrical contact is made by the mercury switch 49, due to the tipping thereof as the tail portion 43b of the arm 43 is moved downwardly, and the motor 38 is set in operation. This results in the lower roller of the wringer being rotated through operation of the belt 39, shaft 37, speed reducing gearing within the housing 36, shaft 35, and sprocket chain 32. The rotating wringer rollers will draw the shirt to the right in Fig. 9 thereby drawing the portions of the shirt submerged in the starch solution from beneath the head 48 of the arm 43 and eventually the portions of the shirt that were submerged in the starch solution will pass between the rollers of the wringer when the excess starch solution will be squeezed therefrom, the starch solution so squeezed from the shirt portions falling in the channel-way and returning to the body of solution in the reservoir 3.

The machine is so timed that immediately as the shirt is entirely discharged from between the rollers of the wringer one of the extensions 84 carried by the sprocket chain 80 will contact with the extended end of the arm 66 fixed to the member 63 and carry said extended end of said arm upwardly. This will restore the member 63 to the position it occupied before it was moved on its pivot 62 by depression of the arm 43 and as a result of such restoring movement of the member 63 the valve mechanism within the housing 71 will be closed to simultaneously shut off passage of air to the cylinder 16 and permit air in the cylinder and conduit 74 to be exhausted through the muffler 75 when the coil springs 24 return the upper wringer roller to its elevated position. Such restoring movement of the member 63 also raises the arm 43 and thereby breaks the electrical circuit leading to the motor 38.

From the foregoing it is plain that all an operator of the machine need do is to fold the shirt and insert the folded shirt in the machine so that the collar and cuffs are submerged in the starch solution and the body of the shirt is located between the rollers of the wringer of the machine. With his hand the operator then depresses the arm 43 so that the head 48 of said arm retains the collar and cuffs of the shirt in a submerged condition in the starch solution. Upon depression of the arm 43 the operator sets the machine in motion, and immediately upon depressing the arm 43 the operator may turn from the machine, as it no longer requires his attention, and prepare the next shirt for the machine. Thus the machine is practically in continuous operation as a succeeding shirt is inserted in the machine as soon as the preceding shirt has been discharged therefrom.

Because of the opposed coil springs 24 of the wringer of the machine the top roller 22 of said wringer may tip if the article passing between the rollers happens to be thicker at one side of the roller than at the opposite side thereof. In this event one of the coil springs 24 will stretch more than the other coil spring. The fit between the extension 19' on the piston rod 19 and the aperture 21' in the upper portion of the member 75

21 is loose enough to permit such tipping of the upper roller of the wringer.

By referring to Figs. 1, 8, and 9 it will be noted that the head 48 of the arm 43 is provided 5 with an upstanding extension 48a. This extension serves as a guard which largely eliminates the likelihood that an operator's hand might be accidentally inserted between the rollers of the wringer of the machine as the operator is working 10 at the machine.

I claim:

1. A starching machine including a reservoir 15 which receives a body of starch solution, a wringer disposed in close proximity to said reservoir and in horizontally offset relation with respect thereto so that articles submerged partially in the starch solution in said reservoir may be drawn therefrom by said wringer, said wringer having a pair of rollers arranged one above the other one of which is movable toward and from the other, and said wringer being so constructed 20 and arranged that articles may be introduced between the rollers of the wringer by moving said articles in the direction of the length of said rollers, and means for rotating a roller of the wringer.

2. A starching machine including a reservoir 25 which receives a body of starch solution, a wringer disposed in close proximity to said reservoir and in horizontally offset relation with respect thereto so that articles submerged partially in the starch solution in said reservoir may be drawn therefrom by said wringer, said wringer having a pair of rollers arranged one above the other one of which is movable toward and from the other, and said wringer being so constructed 30 and arranged that an opening is formed at an end thereof through which articles may be introduced between the rollers of the wringer by moving said articles in the direction of the length of said rollers, and means for rotating a roller of the wringer.

3. A starching machine including a reservoir 35 which receives a body of starch solution, a wringer disposed in close proximity to said reservoir and in horizontally offset relation with respect thereto so that articles submerged partially in the starch solution in said reservoir may be drawn therefrom by said wringer, said wringer having a pair of rollers arranged one above the other one of which is movable toward and from the other, and said wringer being so constructed 40 and arranged that an opening is formed at an end thereof through which articles may be introduced between the rollers of the wringer by moving said articles in the direction of the length of said rollers, and means for rotating a roller of the wringer.

4. A starching machine including a reservoir 45 which receives a body of starch solution, a wringer disposed in close proximity to said reservoir and in horizontally offset relation with respect thereto so that articles submerged partially in the starch solution in said reservoir may be drawn therefrom by said wringer, said wringer having a pair of rollers arranged one about the other one of which is movable toward and from the other, and said wringer being so constructed 50 and arranged that an opening is formed at an end thereof through which articles may be introduced between the rollers of the wringer by moving said articles in the direction of the length of said rollers, and means for rotating a roller of the wringer.

ing said movable roller in the opposite direction, and means for rotating a roller of the wringer.

5. A starching machine including a reservoir 55 which receives a body of starch solution, a wringer disposed in close proximity to said reservoir and in horizontally offset relation with respect thereto so that articles submerged partially in the starch solution in said reservoir may be drawn therefrom by said wringer, said wringer having a pair of rollers arranged one above the other 10 one of which is movable toward and from the other, and said wringer being so constructed and arranged that an opening is formed at an end thereof through which articles may be introduced between the rollers of the wringer by moving said articles in the direction of the length of said rollers, means for moving said movable roller of said wringer in one direction, spring means for moving said movable roller in the opposite direction, and means for rotating a roller of the wringer. 20

6. A starching machine including a reservoir 25 which receives a body of starch solution, a wringer disposed in close proximity to said reservoir so that articles submerged partially in the starch solution in said reservoir may be drawn therefrom by said wringer, said wringer having a pair of rollers arranged in substantial parallelism one above the other, one of which is movable toward and from the other, means for supporting said movable roller so that it may be tipped out of parallelism with respect to the associated roller, said wringer including a frame open at an end of the wringer whereby articles may be introduced between the rollers of the wringer by moving said articles in the direction of the length of said rollers, means for moving said movable roller toward the associated roller, and means for rotating one of the rollers of the wringer. 30

7. A starching machine including a reservoir 35 which receives a body of starch solution, a wringer disposed in close proximity to said reservoir so that articles submerged partially in the starch solution in said reservoir may be drawn therefrom by said wringer, said wringer having a pair of rollers arranged in substantial parallelism 40 one above the other, one of which is movable toward and from the other, means including springs located adjacent to opposite ends of said movable roller for supporting said movable roller so that it may be tipped out of parallelism with respect to the associated roller, said wringer including a frame open at an end of the wringer whereby articles may be introduced between the rollers of the wringer by moving said articles in the direction of the length of said rollers, means for moving said movable roller toward the associated roller, and means for rotating one of the rollers of the wringer. 50

8. A starching machine including a reservoir 55 which receives a body of starch solution, a wringer disposed in close proximity to said reservoir so that articles submerged partially in the starch solution in said reservoir may be drawn therefrom by said wringer, said wringer having a pair of rollers arranged in substantial parallelism 60 one above the other, one of which is movable toward and from the other, means for supporting said movable roller so that it may be tipped out of parallelism with respect to the associated roller, said means including a member for supporting said movable roller, and opposed coil springs attached to said member and anchored to fixed parts of the wringer structure, means for moving said movable roller downwardly comprising an air cylinder provided with a piston thereon, said 65

70 75

5 piston having a piston rod associated therewith which contacts with said member at approximate center of the member to provide a fulcrum therefor, and means for rotating one of the rollers of the wringer, said wringer including a frame open at an end of the wringer whereby articles may be introduced between the rollers of the wringer by moving said articles in the direction of the length of said rollers.

10 9. A starching machine including a reservoir which receives a body of starch solution, a wringer having a pair of rollers, said wringer being so disposed with respect to said reservoir that an article to be starched may be arranged with a 15 part thereof disposed in the starch solution in the reservoir and with another part thereof located between the rollers of the wringer whereby rotation of said rollers of the wringer will draw the portion of the article from the reservoir and 20 squeeze excess starch solution from said part of the article drawn from said reservoir, a movable arm for maintaining the part of the article located in the reservoir in a submerged condition in the starch solution therein, and means operable 25 in response to movement of said arm for rotating a roller of said wringer.

10 10. A starching machine including a reservoir which receives a body of starch solution, a wringer having a pair of rollers, said wringer being so disposed with respect to said reservoir that an article to be starched may be arranged with a 15 part thereof disposed in the starch solution in the reservoir and with another part thereof located between the rollers of the wringer whereby rotation of said rollers of the wringer will draw the portion of the article from the reservoir and 20 squeeze excess starch solution from said part of the article drawn from said reservoir, a movable arm for maintaining the part of the article located in the reservoir in a submerged condition in the starch solution therein, said arm being provided with a head portion that depresses the submerged article part and from beneath which said article part is drawn by the rotating rollers 25 of the wringer, and means operable in response to movement of said arm for rotating a roller of said wringer.

11 11. A starching machine including a reservoir which receives a body of starch solution, a wringer having a pair of rollers, said wringer being so disposed with respect to said reservoir that an article to be starched may be arranged with a 15 part thereof disposed in the starch solution in the reservoir and with another part thereof located between the rollers of the wringer whereby rotation of said rollers of the wringer will draw the portion of the article from the reservoir and 20 squeeze excess starch solution from said part of the article drawn from said reservoir, a movable arm for maintaining the part of the article located in the reservoir in a submerged condition in the starch solution therein, means for rotating a roller of said wringer, and means associated with said arm for controlling operation of the 25 means for rotating a roller of the wringer.

12 12. A starching machine including a reservoir which receives a body of starch solution, a wringer having a pair of rollers, said wringer being so disposed with respect to said reservoir that 15 an article to be starched may be arranged with a part thereof disposed in the starch solution in the reservoir and with another part thereof located between the rollers of the wringer whereby rotation of said rollers of the wringer will 20 draw the portion of the article from the reservoir

and squeeze excess starch solution from said part of the article drawn from said reservoir, a movable arm for maintaining the part of the article located in the reservoir in a submerged condition in the starch solution therein, means for rotating a roller of said wringer, and electrical switch means associated with said arm for controlling operation of the means for rotating a roller of the wringer.

13 13. A starching machine including a reservoir which receives a body of starch solution, a wringer having a pair of rollers, said wringer being so disposed with respect to said reservoir that an article to be starched may be arranged with a 15 part thereof disposed in the starch solution in the reservoir and with another part thereof located between the rollers of the wringer whereby rotation of said rollers of the wringer will draw the part of the article from the reservoir and squeeze excess starch solution from said part 20 of the article drawn from said reservoir, means for moving one of the rollers of the wringer toward the other roller of the wringer, a movable arm for maintaining the part of the article located in the reservoir in a submerged condition 25 in the starch solution therein, means for rotating a roller of said wringer, and means associated with said movable arm for controlling operation of said means for moving a roller of the wringer and said means for rotating a roller of the 30 wringer.

14 14. A starching machine including a reservoir which receives a body of starch solution, a wringer having a pair of rollers, said wringer being so disposed with respect to said reservoir that an article to be starched may be arranged with a 15 part thereof disposed in the starch solution in the reservoir and with another part thereof located between the rollers of the wringer whereby rotation of said rollers of the wringer will draw the part of the article from the reservoir and squeeze excess starch solution from said 20 part of the article drawn from said reservoir, means for moving one of the rollers of the wringer toward the other roller of the wringer, a movable arm for maintaining the part of the article located in the reservoir in a submerged condition 25 in the starch solution therein, means for rotating a roller of said wringer, and means associated with said movable arm for controlling operation of said means for moving a roller of the wringer and said means for rotating a roller of the 30 wringer.

15 15. A starching machine including a reservoir which receives a body of starch solution, a wringer having a pair of rollers one of which is movable toward and from the other, said wringer being so disposed with respect to said reservoir that an article to be starched may be arranged with a 15 part thereof disposed in the starch solution in the reservoir and with another part thereof located between the rollers of the wringer whereby rotation of said rollers of the wringer will draw the part of the article from the reservoir and squeeze excess starch solution from said part of the article drawn from the reservoir, means for moving said movable roller of the wringer toward the other roller of the wringer, said means including an air cylinder and valve means for controlling passage of air 20

to said air cylinder, a movable arm for maintaining the part of the article located in the reservoir in a submerged condition in the starch solution therein, means including an electric motor for rotating a roller of the wringer, and means associated with said movable arm comprising elements cooperating with said air valve means and a switch cooperating with said electric motor for controlling operation of said means for moving a roller of the wringer and said means for rotating a roller of the wringer.

16. A starching machine including a reservoir which receives a body of starch solution, a wringer having a pair of rollers one of which is movable toward and from the other, said wringer being so disposed with respect to said reservoir that an article to be starched may be arranged with a part thereof disposed in the starch solution in the reservoir and with another part thereof located between the rollers of the wringer whereby rotation of said rollers of the wringer will draw the part of the article from the reservoir and squeeze excess starch solution from said

part of the article drawn from the reservoir, means for moving said movable roller of the wringer toward the other roller of the wringer, said means including an air cylinder and valve means for controlling passage of air to said air cylinder, a movable arm for maintaining the part of the article located in the reservoir in a submerged condition in the starch solution therein, means including an electric motor for rotating a roller of the wringer, and means associated with said movable arm comprising elements cooperating with said air valve means and a switch cooperating with said electric motor for controlling operation of said means for moving a roller of the wringer, said wringer including a frame which is open at an end of the wringer whereby a portion of an article to be starched may be introduced between the rollers of the wringer by moving said article portion in the direction of the length of the rollers.

ALLEN R. ALLSUP.
